UNITED STATES PATENT OFFICE.

MARGUERITE HOFFMAN, OF ROCK ISLAND, ILLINOIS, AND PEARSON JOPLING,
DECEASED, LATE OF ROCK ISLAND, ILLINOIS, BY SARAH L. ZERBA, ADMINIS-
TRATRIX, OF ROCK ISLAND, ILLINOIS.

DRILL.

Specification of Letters Patent. Patented Feb. 17, 1920.

1,331,458.

Application filed June 17, 1916, Serial No. 104,339. Renewed July 21, 1919. Serial No. 312,320.

To all whom it may concern:

Be it known that we, MARGUERITE HOFFMAN, a citizen of the United States, and a resident of Rock Island, in the county 5 of Rock Island and State of Illinois, and PEARSON JOPLING, deceased, a late citizen of the United States, and a late resident of Rock Island, in the county of Rock Island and State of Illinois, have invented new and 10 useful Improvements in Drills, of which the following is a specification.

The invention is an improvement in drills, and has for its object to provide a novel form of drill head, wherein oppositely arranged longitudinally extending guide ribs are provided for guiding the drillings to the drive worm, said ribs forming continuations of the ribs of the worm and having shoulders butting the ends of the ribs, 15 and wherein a novel form of bit is provided and formed from a plate of metal stamped and bent to shape, and so connected with the head that it will be firmly held and braced 20 for cutting movement.

25 In the drawings:

Figure 1 is a perspective view of the head, bit and drive worm detached,

Fig. 2 is a partial perspective view showing the connection between the drive worm 30 and the bit,

Fig. 3 is a bottom plan view,

Figs. 4, 5 and 6 are sections on the lines 4—4, 5—5 and 6—6, respectively, of Fig. 2, 35

Fig. 4 looking in the direction of the arrows adjacent to the line,

Fig. 7 is a top plan view of a blank for a modified construction of bit,

Fig. 8 is a front view of the bit formed 40 from the blank shown in Fig. 7 in place in the drill head,

Fig. 9 is an end view of the drill head looking from below,

Fig. 10 is a similar view looking from above,

45 Fig. 11 is an end view of the bit looking from above,

Fig. 12 is an end view looking from below,

Fig. 13 is an end view looking from above of the modified form of head shown in 50 Fig. 15,

Fig. 14 is a similar view from the other end,

Fig. 15 is a perspective view of the drill head,

Fig. 16 is an end view of a modified form 55 of bit formed from the blank shown in Fig. 18,

Fig. 17 is a similar view from the other end, and

Fig. 18 is a plan view of the blank from 60 which the bit is formed.

In the embodiment of the invention shown in Figs. 1 to 6, there is shown a drive worm formed from a strip of metal, and comprising a spirally twisted body 1, having at each 65 end a tongue 2 and 3, respectively. The tongue 2 is adapted for connection with the operating mechanism for the drill, and the tongue 3 for connection with the drill head 4. This tongue 3 as shown, is reduced at each 70 side to form a shoulder 5 at each side of the tongue between the same and the body of the drive worm, and the shoulders 5 are connected at the opposite faces of the tongue by shoulders 6 which extend across the drive 75 worm at the junction of the tongue and body. This tongue 3 is adapted to enter a longitudinally extending similarly shaped recess 7 in the body of the drill head 4, and the shoulders 6 and 5 engage the drill head 80 to limit the inward movement of the tongue with respect to the head.

A set screw 8 is threaded through openings of the head transversely of the recess 7, and the tongue 3 has an opening 9 for 85 permitting the passage of the screw to rigidly connect the drive worm to the head. It will be noticed from an inspection of the drawings that the head 4 is provided at each side edge and on opposite faces with lateral 90 ribs 10, the said ribs extending longitudinally of the head, and each rib has its inner face concave as shown. These ribs are similar but oppositely arranged, and they are guide ribs for guiding the detritus from the 95 drill hole to the drive worm.

It will be noticed from an inspection of Figs. 1 and 2 that each guide rib 10 is extended beyond the upper end of the drill head and that a square shoulder 11 is formed 100

between the inner or connected edge of each rib and the upper face of the head. When the tongue 3 of the drive worm is inserted in the recess 7 the spiral ribs of the drive 5 worm will butt up against these ribs 11 so that the guide ribs 10 will be in effect continuations of the spiral ribs of the drive worm.

The material cut by the bit to be later 10 described, will move along the concave faces of these guide ribs 10 to the spiral ribs of the drive worm, and will be removed from the openings by the spiral ribs. The 15 guide ribs are in effect feed ribs for the ribs of the drive worm. The head is also provided on each face with a longitudinally extending central guide rib 12, the said ribs being parallel with the ribs 10 and spaced apart therefrom, and the said ribs are not 20 directly opposite each other but are offset or staggered as shown more particularly in Figs. 3 and 4. These ribs 12 extend to the cut-away upper end of the head, being of less length than the lateral ribs 10. 25 In use, when the head is turned by means of the drive worm 1, the lower ends of the spiral ribs of the worm will bear against the shoulders 11 so that there will be no possibility of twisting or angular movement of 30 the worm with respect to the head. The drillings which are always confined to the left side of the drill head will be forced up the concave faces of the ribs 10 and up the channel formed between the ribs 10 and 12 35 to the spiral ribs of the drive worm, which will remove them from the drill hole. The lower end of the drill head is provided with a slot 13 for receiving the shank 40 of the bit to be later described, and this slot as shown clearly in Fig. 6, has its bottom wall convex at the center of the slot and concave near each end, and the shank of the bit is shaped to fit this concavo-convex bottom wall. The bit as shown in Figs. 1 and 3, is 45 formed from a plate of suitable material which is stamped to form a blank, which is afterward bent to shape. The bit has a plane shank portion 14 of approximately triangular outline, the bore being adapted to 50 enter the slot or passage 13 and being shaped to fit the concavo-convex bottom wall 13 of the said slot or passage, and wings 15 and 16 at each side of the body, the said wings being also of approximately triangular outline 55 as shown.

At the outer or cutting end the blank is notched at each corner as indicated at 17, the said notches being between the wings 15 and 16 at each side. These wings 15 and 16 60 at each side of the body 14 have their bases outward and those portions of the wings near the bases are bent in opposite directions as clearly shown in Fig. 3, the bent portions being curved as shown. Thus the 65 outer corners of the wings 15 and 16 form

cutting teeth, and the bases of the portions meet at an obtuse angle as shown to form a cutting point at the center of the cutting edge of the bit.

The bit is held in place in the slot or passage of the head by means of a screw or pin 8, which is passed through registering openings in the head and in the shank of the bit. The concavo-convex outline of the bottom of the slot or passage 13 and the correspondingly shaped edge of the base at the body of the bit provide a means for preventing rocking movement of the bit with respect to the head.

In Fig. 7 is shown a blank in a modified 80 form of bit. With this arrangement the blank may be considered as composed of five triangles in the same manner as the blank shown in Fig. 1, namely, a body 19 of triangular form and wings 20 and 21 also of 85 triangular form. The base of the body 19 is designed to engage the passage 13 of the head and this portion of the bit is plane. The wing 20 has its base outward and at the outer angle each wing 20 is notched as shown 90 at 22.

The wings 21 have their bases inward, and these wings 20 and 21 of each side are approximately right-triangles. When the blank is bent on the lines separating the wing 19 95 from the wings 20, the inner walls of the notches 22 will form teeth in the same manner as the inner walls of the notches 17. The wings 20 and 21 are bent in opposite directions in the same manner as shown in 100 Fig. 3.

In Figs. 8 to 12, the head 23 is similar to the head 4, having the lateral ribs 24, and the central ribs 25, and the shoulders 26 at the inner or connected edges of the ribs 24. 105 The head also has the recess 27 in its inner end for receiving the tongue 3 of the drive worm, and the ribs of the worm abut against the shoulders 26 in the same manner as they abut against the shoulders 11 of the construction shown in Fig. 1. The tongue 3 is engaged by holding means which are passed through oppositely arranged openings 28 in the head, and the upper end of the head is provided with a slot or passage 29, corresponding to the slot or passage 13, shown in 115 Figs. 1 to 6 for receiving the shank of the bit, and the bottom wall of the slot or passage is concavo-convex like the bottom wall of the slot or passage 13.

The bit shown in Figs. 8, 11 and 12, comprises a body 30 of approximately triangular outline and having its base shaped to fit the bottom wall of the passage 29, wings 31 and 32 at each side of the body, and a wing 120 33 at the base of the wing 31. These wings 33 are limited by lines passing from the apex of the body 30 to the inner corners of the notches 34. The bases of the wings 31 and 32 and the wings 33 are bent in opposite 125 130

directions as shown in Figs. 11 and 12. It will be understood that the limiting lines between the wings and between the wings and the body are not found in practice, being merely described for convenience, the wings merging gradually into each other.

In Figs. 13 to 15 is shown a modified form of drill head, the head comprising a substantially cylindrical body 35, having oppositely arranged spiral ribs 36. The drill head is provided at one end with a recess 37 for receiving the tongue 3 of the drive worm, and the opposite end of the head is tapering or frusto-conical as shown, and is provided with a transverse slot or passage 38 for receiving the shank of the bit. This passage as will be evident from an inspection of Fig. 15, has its ends at the terminations of the ribs 36, so that when the bit to be later described, is within the slot or passage the corners of the shank will be practically continuations of the ribs 36.

The bit is formed from the blank shown in Fig. 18, the said blank being an approximately rectangular plate 39, having however, the corners at one edge notched deeply as indicated at 40. The blank may be considered as being composed of a body triangular in outline whose base is shaped to fit the bottom of the passage or slot 38, and a wing at each side of the body, the notches 40 being at the outer angles of the substantially triangular wings. The wings are bent in opposite directions in the same manner as the wings 15 and 16 of Fig. 1, the inner walls of the notches 40 forming cutting teeth. The center guide wings 12 of Figs. 3 and 4 are for the purpose of causing the drill to drill straight, preventing it from veering to one side and insuring a straight drill hole. This is of great advantage as it permits the explosive to pass to the extreme end of the hole in a more uniform manner, and the explosive is not strung out. The wings 21 of the bit shown in Fig. 7 are for the purpose of preventing the drillings from falling into the hole back of the drill head and bit, at the point where the drill bit fits down in the recess and up against the drill head. In each construction two screws 53 are provided engaging in opposite directions, for holding the bit firm in the upper part of the drill head.

We claim:-

55 1. A drill head having at each side edge a guide rib, said ribs extending laterally from opposite faces and opposite edges of the head and from one end of the head to the other, and being concave on their inner faces, the head having a central guide rib on each face adjacent to each lateral rib, and having a recess in one end for receiving a drive worm, the lateral ribs being extended beyond the said end of the head and abutting against the ribs of the worm.

2. In combination a drill head having at one end a transversely extending slot, the bottom of the slot being convex intermediate its ends and concave at each end, and a bit having a shank adapted to enter the slot and shaped to fit the bottom thereof, said bit and head having registering openings, and a pin passing through the openings for connecting them together.

3. In combination a drill head having at one end a transversely extending slot, the bottom of the slot being convex intermediate its ends and concave at each end, and a bit having a shank adapted to enter the slot and shaped to fit the bottom thereof.

4. In combination a drill head having at one end a transversely extending slot, the bottom of the slot being convex intermediate its ends, and a bit having a shank adapted to enter the slot and shaped to fit the bottom thereof.

5. In combination, a drill head having a slot provided with a convex bottom wall, and a bit having one end plane and shaped to fit the convex bottom of the slot, the opposite end being notched at each corner, and the corners being bent in opposite directions, said head having a longitudinal outwardly extending guide rib at each face of the bit, and the corners of the bit being bent in the same direction as the ribs.

6. In combination, a drill head having a slot provided with a convex bottom wall, and a bit having one end plane and shaped to fit the convex bottom of the slot, the opposite end being notched at each corner, and the corners being bent in opposite directions.

7. In combination, a drill head having a slot provided with a convex bottom wall, and a bit having one end plane and shaped to fit the convex bottom of the slot.

8. In combination with the driving worm having spiral ribs, a drill head having longitudinal ribs at the opposite side edges and at opposite faces of the head, and having a recess in one end for receiving the drive worm having spiral ribs and having a tongue fitting the recess of the head, the ribs of the head having shoulders butting against the ends of the ribs of the worm.

9. In combination with the driving worm having spiral ribs, a drill head having longitudinal ribs at the opposite side edges and at opposite faces of the head, the ribs of the head having shoulders butting against the ends of the ribs of the worm.

10. A drill bit formed from a substantially rectangular plate of metal having one edge concave and having its corners notched, the corners remote from the concave edge being curved in opposite directions, and the said edge consisting of two portions extending at an obtuse angle with respect to each other from the center of the edge.

11. A drill bit formed from a substan-

tially rectangular plate of metal having one edge concave and having the corners at the opposite edge notched, the said corners being curved in opposite directions.

5. 12. A drill bit formed from a substantially rectangular plate of metal having the corners at one edge notched, and the said corners being curved in opposite directions.

13. A drill bit formed from a substan-

tially rectangular plate of metal having one edge concaved and having the corners at the opposite edge curved in opposite directions.
